METHOD OF MAKING SHOES

Horatio S. Lyness, Lynn, Mass., assignor to United
Shoe Machinery Corporation, Flemington, N. J.,
a corporation of New Jersey

Application March 29, 1944, Serial No. 528,525

6 Claims. (Cl. 12—142)

This invention relates to methods of making shoes and particularly to the making of shoes of the class known as "pumps" in which no part of the upper extends across the instep. The uppers of shoes of this type are frequently composed, at least in the forepart, of material having a considerable capacity for stretching and have a French binding about the foot opening which consists of a strip or tape which is longitudinally elastic to permit the upper to stretch. One marginal portion of the tape is sewed to the outside of the upper adjacent to the foot opening, the free portion of the tape being then folded inwardly over the edge of the upper against its inner surface or the lining and secured to the upper by cross-stitching which permits considerable stretching of the tape and upper about the foot opening.

The proper lasting of such uppers is difficult because, when tension is applied to the lasting allowance of the upper, there being no part of the upper extending over the instep portion, the upper may slip toward the bottom of the last, thus enlarging the foot opening and putting considerable material about the foot opening under tension. When shoes lasted under these conditions are removed from the last, the material about the foot opening contracts and, when the shoe is put on the foot, the material about the foot opening may be again stretched, to the extent to which it was stretched when on the last or more, and may have no further stretch to ease the walking movements of the foot; at any rate, it will be too tight for the foot for which the shoe is intended.

Objects of this invention are to provide a method of making shoes which will prevent enlargement of the foot opening during the lasting operation and which will produce a shoe with the proper shape and size of foot opening, with the elasticity of the upper in the region of the foot opening not only unimpaired but enhanced. Broadly, the method consists in temporarily attaching to the outside of the upper about the foot opening at least in that portion which is liable to be stretched in lasting, for example forwardly from the junction of the vamp with the quarters, an inextensible element, then lasting the upper and, at a later stage in the manufacture of the shoe, removing the inextensible element.

One simple and practical way of practising the method is to include under the cross-stitching by which the French binding tape is secured to the upper an inextensible cord, anchoring the ends of the cord to the upper, lasting the shoe in a usual manner, then releasing the ends of the cord

and withdrawing it from under the cross-stitching. The removal of the cord from under the cross-stitching leaves the stitches of the cross-stitch seam much looser than they would otherwise be, and hence the tape and the stretchable portions of the upper can stretch more freely than when cross-stitching is inserted in the usual way.

These and other aspects of the invention will appear more fully from the following description when read in connection with the accompanying drawings and will be pointed out in the appended claims.

In the drawings,

Fig. 1 is a plan view of an upper having a French binding which has been secured to the upper by cross-stitching, a cord being introduced through a guide on the presser foot of the sewing machine to cause the stitches to embrace the cord without penetrating it;

Fig. 2 is a plan view of a lasted shoe showing the manner of securing the ends of the cord before the upper is lasted;

Fig. 3 is a detail in perspective, partly in section, of parts shown in Fig. 2;

Fig. 4 is a plan view of a lasted shoe showing the ends of the cord released and the cord being withdrawn;

Fig. 5 is an enlarged view of a portion of Fig. 4; and

Fig. 6 is a plan view of the completed shoe, the cord having been withdrawn and the shoe being still on the last.

As illustrated in Fig. 1, the upper may consist of leather quarters 10 of usual construction, for example of leather with a lining, between which and the upper is a usual counter. The rear part of the upper is therefore relatively inextensible.

The forward or vamp portion 12 of the upper may comprise an outer layer of leather backed by a layer of elastic material. That is, the vamp portion 12 may be made of material such as that disclosed in Letters Patent of the United States No. 2,184,261, granted December 19, 1939, in the name of Arthur Vamos. The vamp 12 may be joined to the quarters by a seam 14 or, if desired, a full vamp may be used; that is, the vamp may include the quarters and extend to the back seam 16. In that case, a usual relatively inextensible lining would be used rearwardly of the line 14 and only the forepart or vamp portion 12 would be backed or lined with an elastic material.

In any case, the foot opening 18 of the upper is bound with a longitudinally extensible and elastic tape 20 by first sewing a marginal portion of the tape to the upper 12 by a seam 22

(Fig. 3) and folding the free portion of the tape over the edge of the foot opening and laying it against the inner face of the upper. To hold this portion of the tape in place cross-stitching 24 is inserted by a sewing machine the needle of which vibrates back and forth as the work is fed, giving the thread a zigzag form.

To carry out my method, the pressor foot 26 of the machine is provided with a tubular guide 28 through which a small but strong and inextensible cord 30 is fed in such relation to the needle that the needle passes down through the work first on one side of the cord and then on the other without touching the cord. Thus, the cord is held upon the upper by the thread of the zigzag seam 24.

Each end of the cord is anchored in place by bending it over the bound edge of the upper and placing over it a piece of Scotch tape 32 (Fig. 3) which will, of course, stick to the upper and the cord and hold the cord to the upper temporarily.

The upper is then placed on a last 34 (Fig. 2) and its lower marginal portion tensioned and worked over an insole in the usual manner. During this operation the tension applied to the upper tends to draw the upper down over the conical surface of the last, especially in the region of the throat of the upper, thus enlarging the foot opening. When, however, the stretchable portion about the foot opening is reinforced by the cord 30 as above explained, any substantial enlargement of the foot opening during lasting will be effectively prevented. At any stage in the manufacture of the shoe subsequent to lasting, the pieces of Scotch tape 32 may be pulled off to release the ends of the cord and the cord may be pulled from under the stitches 24. This may be done by pulling on either end of the cord or by engaging an intermediate portion of the cord with a hook 36 (Figs. 4 and 5) and pulling forwardly of the shoe on the cord. The withdrawal of the cord 30 from beneath the stitches 24 leaves the stitches somewhat loose, thus enabling the elastic tape 20 to stretch more freely when the shoe is worn, thus increasing the comfort of the shoe. Furthermore, since the shoe was prevented from stretching during lasting, the shoe may be placed on the foot without substantially stretching the upper. Thus, all the elasticity which the designer of the shoe intended it to have is available to ease the movements of the foot in the action of walking.

Having thus described my invention, what I claim as new and desire to secure by Letters Patent of the United States is:

1. That improvement in methods of making pump shoes the uppers of which consist at least in part of stretchable material which consists in securing a stretchable tape about the foot open-

ing and at the same time temporarily attaching to the outer side of the upper an inextensible member to maintain the normal size of the upper, lasting the shoe, and after the lasting operation removing the inextensible member thus permitting said stretchable material and tape to stretch to their full capacity.

2. That improvement in methods of making pump shoes the uppers of which consist at least in part of stretchable material which consists in securing a stretchable tape about the foot opening by cross-stitching and at the same time introducing an inextensible cord under the cross-stitching, securing the ends of the cord to prevent enlargement of the foot opening, lasting the shoe, and subsequent to the lasting operation releasing the cord and withdrawing it from under the cross-stitching.

3. That improvement in methods of making 20 shoes which consists in temporarily cross-stitching to the outer side of an extensible pump upper about the foot opening an inextensible cord to maintain the normal size of the upper about the foot opening when the upper is subjected to lasting strains, then lasting the upper, and after the upper is lasted releasing the inextensible cord.

4. That improvement in methods of making 30 pumps having extensible uppers which are bound about the foot opening with extensible tape cross-stitched to the upper which consists in including under the cross-stitching an inextensible cord arranged to prevent stretching of the foot opening, then lasting the upper, and after the lasting operation releasing the cord.

5. That improvement in methods of making 35 shoes which consists in temporarily cross-stitching to the outer side of an extensible upper about the foot opening an inextensible cord, anchoring the ends of said cord to maintain the normal size of the upper about the foot opening when the upper is subjected to lasting strains, then lasting the upper, and subsequently removing the inextensible cord to permit unrestricted stretching of the upper.

40 6. That improvement in methods of making 50 pump shoes the uppers of which consist at least in part of stretchable material which consists in securing a longitudinally resilient tape about the foot opening by cross-stitching and at the same time introducing an inextensible cord under the cross-stitching, securing the ends of the cord to prevent enlargement of the foot opening, lasting the shoe, and subsequent to the lasting operation releasing the cord and withdrawing it from under the cross-stitching thereby loosening the stitches to permit the tape to stretch more freely.

HORATIO S. LYNESS.
